UNITED STATES PATENT OFFICE.

AUSTIN F. JACKSON, OF TAUNTON, MASSACHUSETTS, ASSIGNOR TO THE
REED & BARTON CORPORATION, OF SAME PLACE.

DESIGN FOR A SPOON, &c.

SPECIFICATION forming part of Design No. 20,813, dated June 2, 1891.

Application filed May 8, 1891. Serial No. 392,111. Term of patent 7 years.

To all whom it may concern:

Be it known that I, AUSTIN F. JACKSON, residing at Taunton, in the county of Bristol and State of Massachusetts, have invented and produced a new and original Design for the Handles of Spoons, &c., of which the following is a specification, reference being had to the accompanying drawing, the figure of which represents a face view of a spoon the handle 5 of which is designed according to my invention.

For this design I have adopted and devised figures and symbols commemorative of the discovery of America.

15 The leading feature of my design consists in the figures of a king and queen, representing Ferdinand and Isabella, in erect position.

20 *a* indicates the said leading feature, the same appearing as if the king and queen were standing upon a platform or throne, and in connection with an ornamental border *b*, the upper portion of which merges into an overhanging

canopy *c*, centrally of which is the representation of the Spanish coat of arms *d*, from which hang the pendants or tassels *e*, and below such border is a transverse ornamentation *f*, which may be omitted, if desired, the whole appearing on the upper end of the spoon-handle. Upon the shank of the handle are represented the words "Ferdinand and Isabella," which, however, form no part of the design and may be omitted.

25 While I have shown the design of a spoon-handle, it may be used on the handles of knives, forks, ladles, &c.

30 Having thus described my invention, what I claim, and desire to secure by Letters Patent, is—

35 The design for the handles of spoons, forks, knives, &c., as set forth and represented.

AUSTIN F. JACKSON.
